METHOD AND MACHINE FOR PACKAGING

Roy S. Davis, Otsego, Mich.

Application June 2, 1938, Serial No. 211,381

9 Claims. (Cl. 226—14)

The main objects of my invention are:

First, to provide a novel machine and method for packaging articles such as eggs.

Second, to provide a machine of the type described having means for operating on an egg carton filler accommodating a predetermined number of eggs to divide the same into sections accommodating a lesser predetermined number of eggs and for thereafter encasing the resultant sections in individual cartons.

Third, to provide a machine of the type described which is manually operable but well adapted to automatic operation if such is desired.

15 Further objects relating to details and economies of my invention will definitely appear from the description to follow. The invention is defined in the claims.

A structure embodying the features of my invention is illustrated in the accompanying drawings, wherein:

Fig. 1 is a plan view of a machine embodying my invention.

Fig. 2 is an enlarged fragmentary view in section on line 2—2 of Figs. 1 and 4.

Fig. 3 is a fragmentary view in section on line 3—3 of Fig. 1, illustrating certain details of the machine.

Fig. 4 is an enlarged fragmentary view in longitudinal section, further illustrating details of the construction.

Fig. 5 is a view in transverse section through the package resulting from the performance of my method.

35 Fig. 6 is a perspective view illustrating details of the carbon filler in operative relation to the carton or casing therefor.

The present invention deals with a method and machine or apparatus for forming egg filler units 40 and encasing the same in cartons. In practising the method, the eggs or other articles to be packaged are initially placed in a collapsible cellular filler accommodating a predetermined number of articles, for example, three dozen. These

45 fillers, designed to be arranged in tiers or stacks in suitable crates, are widely used in the shipping, storage, and bulk delivery of eggs. The fillers are operated on in the manner to be described to divide the same into three sections having one dozen cells or compartments each by sawing and trimming the large filler. As a final step, the subdivided sections are slidingly inserted, directly following the division and in a single stroke, 50 into the encasing cartons in which the same are

marketed or delivered to the retail trade or consumer.

The machine which I have devised for practising the method is characterized primarily by its simplicity. As described, it is adapted for manual actuation by one or two operators, however it will be apparent as the description proceeds that the machine is well adapted for fully automatic operation in the event circumstances should warrant the same by provisions which will 10 be apparent to those skilled in the art.

Referring to Figs. 5 and 6, wherein I illustrate a filled carton as produced in accordance with my invention, the package in Fig. 6 being partially completed, this carton consists of an outer 15 casing 1 which is adapted to be filled and closed from the end thereof as illustrated in Fig. 6, the same being provided with closure tabs 2 and a hinged end wall 3 of well known type.

The filler insertable within casing 1 consists 20 of a bottom sheet of paper pulp 4 molded to provide the egg receiving seats 6. These seats are adapted to be located in the compartments or cells 7 of a collapsible cellular filler or insert 8. As is well known, such fillers are generally formed 25 to accommodate a predetermined number of eggs, usually thirty-six. The filler 8 which I employ consists in general of the transverse partitions 9 and the longitudinal partitions 10. The transverse partitions 9 are provided with a series of 30 semi-circular apertures 11 by slitting the same with a semi-circular knife and folding the resultant semi-circular tongue 12 180°, as illustrated by dotted lines in Fig. 5. The longitudinal partitions 10 are slotted at 13 for engagement with the 35 transverse partitions 9 within and adjacent the diameter of the apertures 11. It is desirable to remove the tongues 12 adjacent the outermost longitudinal partition 10. Therefore, these outermost apertures may be formed by a punch and 40 die, removing all of the material from a semi-circular area.

Therefore said filler 7 is assembled by interlocking the longitudinal and transverse partitions in obvious manner and thereafter placing 45 the same over the molded bottom member 4 to produce the finished filler 8 which thereafter is filled with eggs or other articles 14 and placed on the feed and discharge table 15 of the packaging machine, with the longitudinal partitions 10 50 disposed longitudinally of the machine, as illustrated in Fig. 1.

The machine consists of the supporting table 16 of which the feed and discharge table 15 is a part, this table being supported on suitable legs or 55

other standards 17 and being provided with a sub-table or shelf 18 whereon is disposed a motor 19.

Referring to Fig. 1, a transverse guide 20 is disposed on feed and discharge table 15 to guide the lateral movement of the filler 8 into position in front of a pushing mechanism generally designated 21. This mechanism consists of a pusher foot or plunger 22 adapted to engage the filler 8 to slide the same longitudinally of the machine, the said plunger being carried on a slidable supporting frame 23 carried by elongated slides 24 guided for longitudinal movement in the ways or tracks 25. These ways are supported in spaced relation to table 16 by standards 26. The pusher member 21 is provided with a handle 27 adapted to be grasped by an operator to shove the filler past mechanisms for subdividing the same, which will now be described.

Table 16 has mounted thereon a pair of angled brackets 28 having upwardly extending walls 29. These brackets are disposed on either side of the line of travel of the filler longitudinally of the machine and serve as supports for the operating mechanisms to be described. On the forward end of the brackets, i. e., on the end toward pusher member 21, there is disposed a transverse screw threaded rod 30 held in place by nuts 31. This rod is encircled by a sleeve 32 carrying a pair of longitudinally extending end folder and side moldboard members 33 whose forward ends 34 are turned outwardly to receive the filler 8 as it is advanced by pusher member 21, engaging the projecting ends 35 of the transverse partitions 9 and folding them rearwardly against the outermost longitudinal partitions 10, as illustrated in Fig. 2.

Sleeve 32 is provided with a pair of slitting knives 36 disposed transversely of the filler adjacent certain of the longitudinal partitions 10 to divide the filler into three equal sections. It will be noted in Fig. 2 that the aforesaid knives extend downwardly only sufficient to sever the portion 37 of partition 9 between the semi-circular aperture 11 and the top of the filler. This, of course, greatly facilitates subdivision of the filler.

Disposed beneath knives 36 are the forwardly extending sheet metal fingers 38, see Figs. 2 and 4, which engage the longitudinal partitions 10 beneath knives 36 to prevent buckling of the partitions during operation of the knives. These fingers are extensions of intermediate moldboards 39 for the sides of the subdivided filler sections, the previously mentioned folder and moldboards 33 serving as the outermost retaining members or guides for the filler as it slides longitudinally of the machine. Accordingly, it will be seen that the filler, both prior and subsequent to the subdivision, is adequately restrained at the sides thereof.

The aforesaid moldboards 33 and 39 are all provided with curved vertical guide and restraining members 40 to prevent upward movement of the filler and all of the knives, moldboards, and retaining members are carried on sleeve 32 for transverse adjustment therewith as a unit. The nuts 41 are adjustable on threaded rod 30 to abut the ends of the sleeve and hold the same in adjusted lateral position.

Table 16 has a pair of journal members 41 depending therebeneath wherein is rotatably mounted a shaft 42 threaded intermediate its length at 43 and adjustably supporting the sleeve 44. On this sleeve a plurality of disk saws are dis-

posed, two, designated by the reference numeral 45, in vertical alinement with the slitter knives 36 and two, designated 46, disposed adjacent the sides of the filler as it moves through the machine. The table 16 is apertured at 47 to receive the saws.

Saws 45, it will be noted, are larger in diameter than saws 46 inasmuch as the former are intended to cut through the bottom molded filler member 4 and also the reduced portion 48 of the transverse partition 9 between the aperture 11 and bottom thereof, thus, in conjunction with slitter knives 36 completely severing the partition at top and bottom. Saws 46 are smaller inasmuch as they serve merely to trim the outermost ends 49 of the bottom filler member and do not cut the rearwardly folded ends 35 of the transverse partitions. The saw carrying sleeve 44 is adjustably held in place on shaft 42 by means of end nuts 50 adjustable on the shaft threads 43.

Shaft 42 is belt driven from motor 19 as illustrated in Fig. 3 and a container or pan 51 is disposed beneath the saws to receive waste falling therefrom.

The sleeves 32 and 44 adjustably mounted on threaded rod 30 and shaft 42, respectively, provide means for positioning the operating instrumentalities laterally of the machine to thereby align the knives, moldboards, and saws relative to the path of travel of the filler. Normally, the latter is suitably guided prior to reaching the knives and saws by means of the side board 52, see Fig. 1. However, it will be understood that variations in the dimensions or relative positioning of the filler members 4, 7 may result in misalignment of the longitudinal partitions with the operating instrumentalities and accordingly the adjusting means is highly desirable. If desired, the knives and saws might also be made individually adjustable on their respective sleeves. However, I have not disclosed specific provisions for accomplishing this as they will occur to those skilled in the art.

After passing the knives 36 and saws 45, 46, the filler is in subdivided form consisting of three sections each accommodating a dozen eggs. It is now necessary to forward the subdivided sections and insert the same in individual cartons or casing members 1. To do this I provide a longitudinally slidable frame 53 which, like pusher frame 23, is secured to the slides 24 traveling longitudinally in the sheet metal ways or tracks 25 on either side of the path of travel of the fillers. The frame 53 has a transverse handle 56 and carries a rotatable rockshaft 51 having secured thereto a pair of rods 58 to which is in turn secured a rake-like puller or forwarding member 59. It is the function of the last named member to engage the rear side of the subdivided fillers as illustrated in Fig. 4 and advance the same towards the discharge end of the machine, when the frame 53 is manually retracted by an operator. From the foregoing, it is evident that the machine may be operated by manually reciprocating either the pusher frame 23 or forwarding member 59.

I contemplate means for returning the forwarding member 59 to position for engagement with a subsequent group of fillers without interference with the said subdivided fillers on the return stroke to position behind the same. Such means takes the form of elevated tracks or ways 60 disposed on bracket walls 29. The said ways have downwardly curved front ends 61 and at the rear ends thereof cam-like switch members 75

62 are pivoted thereto at 63. The member 59, as illustrated in Fig. 4, is provided with a roller or follower 64 and it will be apparent that upon movement of the member 59 rearwardly, or to the left as illustrated in Fig. 4, the said switches 62 will rise, allowing passage of the roller 64 therebeneath. Thereafter, switch members 62 drop into position in the normal path of travel of the roller, so that on return movement of the member 59 to the right, as illustrated in Fig. 4, the roller will travel up the switch member 62 onto the way 60, thus elevating member 59 during its return stroke and lowering the same at the end of the said return, as illustrated in dotted lines in Fig. 4. To assure that the puller member 59 will be fully restored to vertical operating position behind the fillers, I provide a coil spring 65 encircling rockshaft 57, having one end thereof anchored behind a suitable portion 20 of the frame 53, as at 66, and the other end 67 thereof engaging a rod 58 to urge the puller member 59 in clockwise direction, as viewed in Fig. 4.

The top guides 68, 69 suitably attached to ways 25 54 insure against upward movement of the fillers during the movement just described.

On the discharge end 70 of the machine I dispose a carton receiving and positioning plate 71 in a plane beneath table 16, whereby to bring 30 the bottom edge of the carton opening flush with the table 16 upon which the fillers are traveling with the end closure flaps 3 of the cartons folded beneath the cartons while receiving the fillers, as illustrated in dotted lines in Fig. 1. The cartons 35 are disposed on the discharge plate 71 as illustrated in Figs. 1 and 3 with the forward end restrained vertically by the adjustable cam holding members 72 on a transverse rod 73 preferably supported on the guide tracks of the machine. These members 72 are, as illustrated in Fig. 1, spaced transversely so as to engage the cartons only at the vertical walls thereof, thereby preventing distortion of the cartons such as would prevent or impede insertion of the fillers 45 therein. The rear end of the cartons is engaged by a collapsible pivoted or spring finger 74 which permits withdrawal of the filled cartons.

The fillers are drawn rearwardly into the casings by sliding manipulation of frame 53, and 50 inasmuch as the projecting ends 35 of transverse partitions 9 have been folded against the outermost longitudinal partitions 10 and thereafter maintained in this position by moldboards 33, entry of the filler in the cartons or casings is 55 effected with facility.

It is apparent that my device may be operated rapidly by two operators, one to load the fillers 8 and the other to remove and close the filled cartons. Either operator may reciprocate frames 60 23 and 53. If desired, however, a single operator is well able to operate the machine by himself. The adaptability of my device to completely automatic operation is likewise apparent, it being necessary merely to provide some well known power applying device for reciprocating slides 65 24. Such means has not been illustrated because it is not desired to complicate the disclosure, however it is to be understood that the appended claims shall not be necessarily limited to a manually operated device unless the terms thereof so state.

I have illustrated and described my improvements in an embodiment which is very practical. I have not attempted to illustrate or describe 75 other embodiments or adaptations as it is believed

this disclosure will enable those skilled in the art to embody or adapt my improvements as may be desired.

Having thus described my invention, what I claim as new and desire to secure by Letters 5 Patent is:

1. A machine for packaging eggs and the like arranged in fillers having transverse partitions provided with apertures and longitudinal partitions extending through the apertures, comprising means for advancing said fillers through the machine in a direction parallel to the longitudinal partitions, means for slitting said transverse partitions at the apertures from above to partially sever the transverse partitions adjacent and parallel to the longitudinal partitions, means for sawing said transverse partitions in vertical alignment with the slitting means to completely sever said transverse partitions and form subdivided filler sections, side and intermediate moldboard 10 means to engage the sides of the filler sections to guide and restrain the same during longitudinal movement, means for mounting said slitting, sawing, and moldboard means for adjustment transversely as a unit, means for folding the laterally 15 projecting ends of said transverse partitions rearwardly of the path of travel of the filler, means for supporting a plurality of individual tubular casings corresponding in number to the sections in the path of travel of the sections, and means for advancing said sections endwise each into a 20 corresponding individual casing.

2. A machine for packaging eggs and the like arranged in fillers having transverse partitions provided with apertures and longitudinal partitions 30 extending through the apertures, comprising means for advancing said fillers through the machine in a direction parallel to the longitudinal partitions, means for slitting said transverse partitions at the apertures from above to 35 partially sever the transverse partitions adjacent and parallel to the longitudinal partitions, means for sawing said transverse partitions in vertical alignment with the slitting means to completely sever said transverse partitions and form subdivided 40 filler sections, moldboard means to engage the sides of the filler sections to guide and restrain the same during longitudinal movement, means for folding the laterally projecting ends of said transverse partitions rearwardly of the 45 path of travel of the filler, means for supporting a plurality of individual tubular casings corresponding in number to the sections in the path of travel of the sections, and means for advancing said sections endwise each into a 50 corresponding individual casing.

3. A machine for packaging eggs and the like arranged in fillers having transverse partitions provided with apertures and longitudinal partitions 55 extending through the apertures, comprising means for cutting said transverse partitions at the apertures from above to partially sever the transverse partitions, means for sawing said transverse partitions at points in vertical alignment with the cutting means to completely sever 60 said transverse partitions and form subdivided filler sections, means for supporting a plurality of tubular casings in the path of travel of the sections, and means for advancing said sections endwise each into a corresponding individual 65 casing.

4. A machine for packaging articles inserted in cellular fillers, comprising means for advancing a filler with articles disposed in the cells thereof in a direction parallel to a dimension of the 75

- filler, means for subdividing said filler parallel to the direction of its movement into a plurality of individual sections, means for trimming projecting edge portions on the outermost edges of said fillers, means for supporting a plurality of individual tubular casings in the path of movement of said sections, and means for moving said individual sections endwise into said individual casings following said subdivision and trimming.
- 5 5. A machine for packaging articles inserted in collapsible cellular fillers, comprising means for advancing a filler in a direction parallel to a dimension of the filler, means operative during the advancing movement for subdividing said filler parallel to the direction of its movement into a plurality of individual sections, means for supporting a plurality of individual cartons in the path of movement of said sections, and means for placing said sections in said individual cartons following said subdivision.
- 10 6. A machine for packaging eggs and the like subsequent to the disposition thereof in cellular fillers, comprising means for slitting said fillers parallel to a dimension thereof and adjacent a partition thereof to divide the filler into a plurality of sections, means for supporting individual tubular casings, one for each section, adjacent the discharge end of the machine, and means for advancing said filler through said slitting means and inserting said sections endwise into said individual casings.
- 15
- 20
- 25
- 30

7. A machine for packaging eggs and the like subsequent to the disposition thereof in cellular fillers, comprising upper and lower cutting means for cutting said fillers from the top and bottom thereof to divide the same into a plurality of sections, means for supporting individual cartons one for each section, adjacent the discharge end of the machine, and means for advancing said filler through said cutting means and placing said sections into said individual cartons.

8. The method of packaging articles such as eggs and the like, comprising inserting said articles into cellular fillers of predetermined capacity, sliding said fillers longitudinally, bending projecting ends of the partitions of the fillers rearwardly of the direction of travel thereof, subdividing said fillers into sections during said sliding movement, and inserting the sections into individual tubular cartons by a single longitudinal stroke following the subdivision.

9. The method of packaging articles such as eggs and the like, comprising inserting said articles into cellular fillers of predetermined capacity, moving said fillers and subdividing said fillers into sections of equal aliquot capacity during the movement, and inserting the sections into individual cartons by a longitudinal shifting movement of the sections following the subdivision in the direction of the first named movement.

ROY S. DAVIS.
